UNITED STATES PATENT OFFICE.

AUSTIN S. SHEPARD, OF SAN DIEGO, CALIFORNIA.

ADJUSTABLE SHADE AND CURTAIN POLE HANGER.

1,101,573.

Specification of Letters Patent. Patented June 30, 1914.

Application filed April 18, 1913. Serial No. 761,887.

To all whom it may concern:

Be it known that I, AUSTIN S. SHEPARD, a citizen of the United States, and a resident of San Diego, county of San Diego, 5 and State of California, have invented certain new and useful Improvements in Adjustable Shade and Curtain Pole Hangers, of which the following is a specification.

My invention relates to hangers to be mounted on the sides of the window-casing for holding both the shade and curtain poles, or either of them, and more particularly those which are adjustable so that different length poles may be used without 10 cutting or fitting the same, and the objects of my invention are, first, to provide hangers the holding parts of which are adjustable so as to facilitate the placing of the poles, second, to provide such hangers that 15 are simple, easily installed, easily adjusted and present a pleasing appearance to the eye, and third, to provide such hangers that are easily constructed.

With these and other objects in view, 20 as will appear hereinafter, my invention consists in certain novel features of construction, combination and arrangement of parts as will be hereinafter described in detail and particularly set forth in the appended claims, reference being had to the accompanying drawings and to the characters of reference thereon, which form a part of this specification, in which:

Figure 1 is an elevational view of my 25 hangers shown in position with the shade and the curtain poles mounted thereon, Fig. 2 is a perspective view of the hanger support showing the shade and curtain pole hanger mounted therein ready for use, Fig. 3 is a side view of the hanger support, Fig. 4 an edge view thereof, Fig. 5 a side view of one of the shade pole hangers, and Fig. 6 is a side view of one of the curtain pole 30 hangers.

Similar characters of reference refer to similar parts throughout the several views.

The hanger supports 1, shade hanger 2, shade hanger 3 and curtain hangers 4, constitute the principal parts of my device.

The supports 1 are shaped as shown best in Fig. 2, the middle portion being raised relatively to the edges as shown best in Fig. 4. They are provided with a plurality of holes 1^a adapted for screws for attaching them to the window-casing and they are provided centrally with slots 1^b, the upper and lower

edges of which are provided with a plurality of notches 1^c and 1^d, the notches marked 1^c in the top portion being considerably deeper than those marked 1^d in the lower portion. These supports are the same for both sides of the window-casing. Each of these is provided with a curtain hanger 4 shaped as shown best in Figs. 2 and 6. They are preferably constructed of 60 metallic sheet and provided with a circular notch 4^a adapted for the curtain pole. At the other end of the curtain hanger 4 the metal is bent at right angles a portion in one direction, marked 4^b, and the other portion in the opposite direction, marked 4^c. This is shown best by the dotted lines in 65 Figs. 1 and 2. They are adapted to fit into the slot 1^b so that the edges extend into the notches in the support 1 and the 70 portion 4^b and 4^c hold the hanger in its position in the support, but it may be moved from one notch to the other by raising the hanger 4 into the top notch when the lower portion may be moved to the next notch, 75 or several notches if desired, then inserted in the top notch again and the lower edge moved to the notch opposite to the one in which the top edge is inserted.

The shade hangers 2 and 3 are constructed 80 of the same as the supporting end but are shorter and one of them is provided with a round hole, which is marked 2^a for the purpose of illustration, and the other provided with a narrow notch 3^a adapted for 85 the usual shade pole.

Though I have shown and described a particular construction, combination and arrangement of parts, I do not wish to be limited to this particular construction, combination and arrangement, but desire to include in the purview of my invention the construction, combination and arrangement substantially as set forth in the appended 90 claims.

It is obvious that with this construction there are provided shade and curtain pole hangers the hanging portion of each of which may be adjusted in the supports; that they may be adjusted at both ends; that the 95 construction consists of metallic sheet throughout, thus making the construction simple; that the device is readily adjustable, but will not readily get out of order, that the device may be used for shades only or 100 for curtains only, or for both shades and curtains.

Having thus described my invention, what I claim as new and desire to secure by Letters Patent, is:

1. In shade and curtain pole hangers, the combination of two supporting plates each provided with a central slot therein, a plurality of notches in the top edge of said slot, a plurality of shallower notches in the bottom edge thereof, a curtain pole hanger consisting of a metallic piece provided with oppositely disposed flanges at right angles thereto at the supporting end thereof mounted in each slot with its upper and lower edges engaging said slot, said curtain pole hanger being narrower than the slot, and oppositely disposed notches whereby said curtain pole hanger may be raised in one of said notches and its lower edge moved to another notch.
2. In shade and curtain pole hangers, the combination of two supporting plates each provided with a central slot therein, a plurality of notches in the top edge of said slot, a plurality of shallower notches in the bottom edge thereof, a curtain pole hanger consisting of a metallic piece provided with oppositely disposed flanges at right angles thereto at the supporting end thereof mounted in each slot with its upper and lower edges engaging said slot, said curtain pole hanger being narrower than the slot, oppositely disposed notches whereby said curtain

35 pole hanger may be raised in one of said notches and its lower edge moved to another notch, and a shade pole hanger provided with like flanges and similarly mounted in the slot in said plate.

3. In shade and curtain pole hangers, the combination of two metallic wall plates each provided with a slot centrally therein, a plurality of oppositely disposed notches in the upper and lower edges of said slot, the upper notches being considerably deeper than the lower one, a metallic shade pole hanger and a metallic curtain pole hanger made in 45 one piece, each provided with oppositely disposed lugs integral therewith on the supporting ends of said shade and curtain pole hangers and each of such width adjacent to its position in the notches in said slot in 50 said metallic plate whereby each may be moved from one slot to the other by raising the same into the upper slot, then moving the lower edge to another slot, then moving the upper edge to the slot opposite 55 thereto.

In testimony whereof, I have hereunto subscribed my name in the presence of two subscribing witnesses.

AUSTIN S. SHEPARD.
